UNITED STATES PATENT OFFICE

2,623,428

SELF-ADJUSTING PIPE WRENCH OF A
SPRING IMPELLED TRIGGER ACTU-
ATOR TYPE

John V. Larson, Chicago, Ill.

Application April 9, 1947, Serial No. 740,455

2 Claims. (Cl. 81—99)

1

This invention relates to hand tools and more particularly to self-adjusting pipe wrenches, although certain features thereof may be employed with equal advantage for other purposes.

It contemplates more especially the provision of improved hand tools of the pipe wrench type embodying self-closing expedients comprising the subject matter of United States Letters Patents 1,602,620, 1,830,033 and 2,351,821 which have been simplified in their construction to increase the capacity and to substantially reduce the manufacturing costs thereof.

One object of the present invention is to simplify the construction and improve the operation of devices of the general character mentioned.

Another object is to provide improved self-closing relatively pivotal serrated jaws that cooperate in different positions of relative adjustment to effectively grasp different types of articles.

Still another object is to provide self-closing relatively pivotal jaws having improved spring actuator mounts and movement in assembled relation therewith.

Other objects and advantages will appear from the following description of an illustrated embodiment of the present invention.

In the drawing:

Figure 1 is a side view in elevation of a pipe wrench embodying features of the present invention.

Figure 2 is an edge view of the pipe wrench shown in Figure 1, viewed from the open jaw side thereof.

Figure 3 is an enlarged fragmentary side view in elevation of the jaws with parts thereof broken away and shown in section to clarify the illustration.

Figure 4 is a fragmentary sectional view taken substantially along line IV—IV of Figure 3.

Figure 5 is an enlarged edge view in elevation of the jaw structure view to correspond with the showing in Figure 2, parts thereof being broken away and shown in section to illustrate the self-closing spring assembly.

Figure 6 is an enlarged fragmentary plan view of the fixed jaw showing the extended serrated gripping face thereof.

The structure selected for illustration is not intended to serve as a limitation upon the scope or teachings of the invention, but is merely illustrative thereof. There may be considerable variations and adaptations of all or part of the teachings depending upon the dictates of commercial practice.

The illustrated embodiment comprises an elong-

2

gated wrench handle 10 that is forged or cast from an alloy steel composition to present a somewhat tapered manipulating shank. The handle shank 10 has rounded transversely extended integral webs 11—12 formed near the free end thereof to terminate in an enlarged circular boss 13 through which a hole 14 is provided to lighten the construction and afford the hanging support thereof from a suitable vertical wall anchor, such as a nail. The shank 10 tapers slightly to terminate in a fixed or stationary jaw 15 that has an enlarged arcuate surface 16 provided with serrations or teeth 17 over the entire gripping surface thereof. The fixed or stationary jaw 15 projects from a somewhat enlarged circular boss 18 formed integral therewith at its jointure with the handle shank 10 to serve as a pivoting expedient for a movable jaw 19. The movable jaw 19 is provided with correspondingly shaped and sized furcated bosses 20, 21 that are complementary to the fixed jaw boss 18 that is received therebetween to freely rotate thereon without any lateral play therein. The fixed jaw boss 18 and the complementary furcated bosses 20, 21 are provided with eccentrically positioned and aligned apertures 22, 23 and 24, respectively, to receive a pivot pin such as a rivet 25 therethrough that can be swaged (Figure 2) at the projecting end 26 thereof (Figure 4) to retain the parts in assembled relation and provide for the pivoting of the movable jaw 19 relative to the fixed jaw 15. The movable jaw 19 has accentuated triangular trigger extensions 27, 28 formed integral with the movable jaw bosses 20, 21 to accommodate the thumb of the user for quickly opening the movable jaw 19 relative to the fixed jaw 15 to accommodate a round or polygonal pipe or fastener such as a nut therebetween.

It is to be noted that the spaced trigger extensions 27, 28 accommodate the handle 10 therebetween while the movable jaw 19 is solid in construction and has an extended gripping surface 29 substantially conforming to the extended gripping surface 17 of the stationary jaw 15. The extended gripping surface 29 has a straight serrated rectangular portion 30 to confront and cooperate with the stationary jaw arcuate gripping surface 17, for grasping round pipe or polygonal fasteners such as nuts therebetween. The flat gripping surface 30 of the movable jaw 19 extends rearwardly in the direction of the handle 10 to terminate in a right angular shoulder 31 which extends for a comparatively short distance to merge with another serrated gripping surface 32 that is at an acute angle with the flat extended

gripping surface 30. The angular gripping surface 32 confronts and co-operates with a serrated flat gripping extension 33 of the comparatively wider arcuate gripping surface 17 of the stationary jaw 15. The gripping surface extension 33 is provided on the boss 18 of the handle 10 so that smaller pipe or preferably polygonal fasteners such as nuts can be effectively turned to provide an appreciable greater capacity for the pipe wrench that also serves as a combination nut turning wrench as well by reason of the compound gripping surfaces 30, 32, provided on the movable jaw 19.

By thumbing the trigger extensions 27, 28 in a clockwise direction (viewed from Figure 3) the jaws 15, 19 can be readily opened to accommodate the work that is to be turned therewith. By thumbing the triggers 27, 28 in a counter-clockwise direction (viewed from Figure 3), increased pressure can be imparted to the pipe or nut which is being grasped between jaws 15, 19 to increase the gripping action thereon, under extreme conditions to initiate the gripping action and procure more effective results therewith.

In order to render the movable jaw 19 self-adjusting toward the stationary jaw 15 to accommodate the work therebetween and to effectively grasp such without requiring the use of two hands, a flat spiral coil spring 34 is confined within an annular recess 35 provided in the face of the boss 21 of the movable jaw 19. The flat spiral coil spring 34 has an enlarged circular extremity 36 formed thereon to serve as a complement of a circular recess 37 drilled or otherwise provided in the central boss 38 defining the inward shoulder of the annular spring receiving recess 35. The recess 37 is drilled therein proximate to the periphery thereof to establish communication with the annular recess 35 so that the enlarged spring extremity 36 can rest therein and serve to anchor the flat spiral coil spring 34 which surrounds the central boss 38. The other extremity of the flat spiral coil spring 34 has an enlarged bent extremity 39 that embraces a pin 40 which is press fitted into a recess 41 provided in the boss 18 within the region of the annular recess 35 to serve as an anchor for the outside extremity of the flat spiral coil spring 34. The pin 40 projects through an elongated arcuate slot 41' provided in the base of the annular recess 35 to permit the rotary oscillation of the movable jaw 19 between the limits of the slot 41'.

With this arrangement, the flat spiral coil spring 34 will normally urge the movable jaw 19 toward the stationary jaw 15 to effect their extreme approach within the limit defined by a movable jaw straight edge 42 which will abut against lateral shoulders 43 defined by the web of the extended gripping jaw surface 16. As a result, the attendant can thumb the triggers 27, 28 in a clockwise direction to open the movable jaw 19 relative to the stationary jaw 15 to any desired distance within the limit defined by a shoulder 44 (Figure 3) formed on the movable jaw 19 along an edge from which the triggers 27, 28 extend. The shoulder 44 engages the handle shank 10 in the extreme open position of the movable jaw 19 relative to the stationary jaw 15 (Figure 3).

In order to conceal the flat spiral coil spring 34 and preclude any foreign substance from entering the annular recess 35, a washer or circular plate 45, having an eccentrically disposed pivot pin receiving aperture 46, is disposed over the pivot pin 25 (Figure 5) prior to swaging the plain

end 26 thereof (Figure 4). The swaging of the plain pin end 26 confines the cover plate or washer 45 in position for peripheral contact with the boss 21 to serve as a cover for the annular recess 35 with the flat spiral coil spring 34 confined therein. It should be noted that the boss 21 could be readily recessed or countersunk around the periphery of the annular recess 35 to accommodate the washer or plate 45 so that the latter will be flush with the surface of the movable jaw 19 and the triggers 27, 28 after being assembled on the pin 25 for retention of the swaging of the plain pin end 26.

With the arrangement of parts and structural features described above, it will be apparent that the compound movable jaw 19 that confronts the compound stationary jaw 15 accommodates both round and polygonal shapes so that the wrench can be utilized as a conventional pipe wrench as well as a nut turning wrench. This has been accomplished with a self-adjusting instrumentality which affords single hand manipulation and enables effective turning operations in a speedy manner without entailing any appreciable time or inconvenience.

While I have illustrated and described a preferred embodiment of this invention, it must be understood that the invention is capable of considerable variation and modification without departing from the spirit of the invention. I, therefore, do not wish to be limited to the precise details of construction set forth, but desire to avail myself of such variations and modifications as come within the scope of the appended claims.

I claim:

1. A hand tool comprising a handle member, a fixed jaw on said handle member, said fixed jaw having a serrated arcuate gripping surface and a serrated straight surface contiguous therewith, a movable jaw pivoted to said handle member in confronting relation with said fixed jaw, said movable jaw having a serrated gripping surface to co-operate with said fixed jaw in different positions of relative adjustment therewith, a pivot pin extending between said fixed and movable jaws, furcated trigger extensions formed integral with said movable jaw to enable the thumb actuation thereof, spring means for normally urging said movable jaw relative to said fixed jaw, a circular recess in one side of said movable jaw, said recess extending around said pivot pin and being eccentric thereto, said circular recess having an elongated arcuate slot therein, and a spring anchoring pin extending through said elongated arcuate slot and attached to said handle member, said spring means comprising a spiral flat spring in said recess, one end of said spring being attached to said movable jaw within said recess at a point offset from said pivot pin, the other end of said spring being anchored to said anchoring pin.

2. A hand tool comprising an elongated handle member, a fixed jaw formed on one end of said handle member, said fixed jaw having a serrated arcuate gripping surface of greater expanse than the thickness of said handle, and having a serrated straight gripping surface extension of the same width as the thickness of said handle, a movable jaw pivoted to said handle member to confront said fixed jaw, a pivot pin extending between said fixed and movable jaws, said movable jaw having compound serrated gripping surfaces to co-operate with the serrated gripping surfaces of said fixed jaw in different positions of relative adjustment, spring means for nor-

mally urging said movable jaw toward said fixed jaw, a circular recess in one side of said movable jaw, said recess extending around said pivot pin and being eccentric thereto, said circular recess having an elongated arcuate slot therein, and a spring anchoring pin extending through said elongated arcuate slot and attached to said handle member, said spring means comprising a spiral flat spring in said recess, one end of said spring being attached to said movable jaw within said recess at a point offset from said pivot pin, the other end of said spring being anchored to said anchoring pin.

JOHN V. LARSON.
